US0D1009922S

(12) **United States Design Patent** (10) Patent No.: **US D1,009,922 S**
 Stone et al. (45) Date of Patent: ** Jan. 2, 2024

(54) **CELL COUNTER DISPLAY SCREEN WITH GRAPHICAL USER INTERFACE**

(71) Applicant: **LIFE TECHNOLOGIES CORPORATION**, Carlsbad, CA (US)

(72) Inventors: **Laurel Stone**, Veneta, OR (US); **Emily Zink**, Redmond, WA (US); **Sean Zimmerman**, Encinitas, CA (US); **Nicholas Diliani**, Mountainlake Terrace, WA (US)

(73) Assignee: **LIFE TECHNOLOGIES CORPORATION**, Carlsbad, CA (US)

(**) Term: **15 Years**

(21) Appl. No.: **29/887,889**

(22) Filed: **Mar. 24, 2023**

Related U.S. Application Data

(62) Division of application No. 29/758,178, filed on Nov. 12, 2020, now Pat. No. Des. 983,813.

Primary Examiner — Cary M Robinson

(57) **CLAIM**

The ornamental design for a cell counter display screen with graphical user interface, as shown and described.

DESCRIPTION

FIG. 1 is a view of a first embodiment of our new design; and,

FIG. 2 is a view of a second embodiment our new design. The broken lines showing a display screen and portions of the graphical user interface form no part of the claimed design.
